UNITED STATES PATENT OFFICE.

THOMAS B. BOWMAN, OF CHICAGO, ILLINOIS.

RAIL-ANCHOR.

1,107,484.

Specification of Letters Patent. Patented Aug. 18, 1914.

Application filed June 3, 1914. Serial No. 342,742.

To all whom it may concern:

Be it known that I, THOMAS B. BOWMAN, a citizen of the United States of America, and a resident of Chicago, in the 5 county of Cook and State of Illinois, have invented certain new and useful Improvements in Rail-Anchors, of which the following is a specification.

This invention relates to improvements in 10 rail anchors and the object of the invention is to provide a device of this character which may be made of a single malleable casting adapted to be secured to the web of the rail and having one member engag- 15 ing the base of the rail and a shoe or lug adapted to project below the rail and engage the tie to prevent the rail from "creeping".

The invention, in its preferred embodiment, 20 comprises a single casting adapted to hug part of the base of the rail, with one member extending upwardly alongside of the web of the rail and having an integral locking device or bolt passing through an 25 opening in said web, the casting having a shoe or lug projecting downwardly beneath the rail to contact with the tie, the shoe or lug preferably engaging the tie at some distance beneath the base of the rail.

30 The invention will be hereinafter more particularly described and then definitely claimed.

In the drawings accompanying and forming part hereof: Figure 1 is a side elevation of part of a rail having my rail anchor applied thereto. Fig. 2 is an end elevation of my device applied to a rail, the rail being shown in section. Fig. 3 is a side elevation of a modified form. Fig. 4 is an end elevation of the modified form, applied to a rail, the rail being in section. Fig. 5 is a perspective view of the rail anchor shown in Figs. 1 and 2, detached.

Referring now to the details of the drawings by numerals: 1 designates my rail anchor having a horizontally inclined member 2 to co-act with the upper surface of the base 3 of a rail, a vertical member 4 projecting upwardly from said inclined member 2 so as to be substantially parallel with the web 5 of the rail. The vertical member 4 is preferably provided with an integral securing device 6 which is adapted to project through an opening in the web 5 of the rail. This integral securing device is slotted as indicated at 7 so that its ends may be

bent in opposite directions and thus secure the rail anchor to the web of the rail; or a cotter 8 may be passed through perforations shown in dotted lines at 9 in the projecting end of the securing device 6. The rail anchor extends upwardly against the rail as indicated best in Fig. 1 and then projects downwardly at some distance to form a shoe 10. The lower end of the shoe 10 is preferably formed with an offset rib 12 so that the shoe will contact with a tie at some considerable distance below the base of the rail so that I am enabled to utilize the base of the rail to take the stress of creepage. The 65 shoe 10 is reinforced by means of a rib 14 connecting the downwardly projecting shoe 10 with the main part of the casting as clearly shown in Fig. 1. At the left hand end of Fig. 1 is illustrated a strengthening 70 projection 15 which is provided with a short lug 16 projecting transversely of the rail and extending under the same as indicated in the sectional view, Fig. 2.

In Figs. 3 and 4 is illustrated a modification of my invention. This construction is also formed of an integral casting embodying substantially the same features set forth in Figs. 1 and 2. However, in this modification, the vertical member 20 which 80 is secured to the web of the rail is extended upwardly and provided with a cam surface 22 which is adapted to co-act with the under side of the head of the rail. In this form the point at which the vertical member 20 90 is secured to the web of the rail is at one side of the casting as indicated in dotted lines in Fig. 3. In this form the lug 16 of Fig. 2 may be dispensed with, if desired, for a somewhat equivalent effect is produced by 95 having the cam surface 22 co-act with the under side of the rail head. I desire to call particular attention to the fact that the part which engages the upper side of the base of the rail is formed on a curved line, as indicated at 24 in Fig. 3; also the fact that the cam surface 22 bearing on the under surface of the head of the rail is of such curvature that when pressure is exerted on the toe of the casting, it acts as a cam and 105 in combination with the bearing on the top of the base of the rail, a wedge effect is produced.

From the foregoing and accompanying drawings it will be seen that I have provided a one-piece rail anchor of very simple construction and of great effectiveness in

practical operation. In addition to its being made so simple that no threading or tapping is required, it will be observed that the anchor utilizes the rail base itself to take the stress of the creepage. It is absolutely a one-piece device. I am aware that various forms of rail anchors have heretofore been suggested but I regard my device essentially different from any of those here-
10 tofore proposed.

What I claim as my invention is:

1. As an improved article of manufacture, a rail anchor comprising a single piece of material arranged to contact with the base 15 of a rail and having one member projecting upwardly therefrom to co-act with the web of the rail, said member having an integral securing device, and the bottom of the anchor having a shoe or lug projecting down-
20 wardly therefrom to bear against the side of a tie and prevent "creeping", substantially as described.
2. As an improved article of manufacture, a rail anchor comprising a single piece of material arranged to contact with the base 25 of a rail and having one member projecting upwardly therefrom to co-act with the web of the rail, said member having an integral securing device, and the bottom of the anchor having a shoe or lug projecting down-
30 wardly therefrom to bear against the side of a tie and prevent "creeping", said shoe or lug being formed to contact with the tie at some distance below the base of the rail,
35 substantially as described.
3. As an improved article of manufacture, a rail anchor comprising a single piece of material arranged to contact with the base 40 of a rail and having one member projecting upwardly therefrom to co-act with the web of the rail, said member having an integral

securing device with a split end, and the bottom of the anchor having a shoe or lug projecting downwardly therefrom to bear against the side of a tie and prevent "creep-
45 ing", substantially as described.

4. As an improved article of manufacture, a rail anchor comprising a single piece of material arranged to contact with the base of a rail and having one member projecting 50 upwardly therefrom to co-act with the web of the rail, said member having an integral securing device adapted to pass through said web and a cam shaped upper end arranged to engage with the under surface of the head 55 of the rail, and the bottom of the anchor having a shoe or lug projecting downwardly therefrom to bear against the side of the tie to prevent creeping, substantially as de-
scribed.

5. As an improved article of manufacture, a rail anchor comprising a single piece of material arranged to contact with the base 60 of a rail and having one member projecting upwardly therefrom to co-act with the web 65 of the rail, said member having an integral securing device adapted to pass through said web and a cam shaped upper end arranged to engage with the under surface of the head of the rail, the part contacting with 70 the base of the rail having a curved surface, and the bottom of the anchor having a shoe or lug projecting downwardly therefrom to bear against the side of the tie to prevent creeping, substantially as described.

In testimony whereof I affix my signature in presence of two witnesses.

THOMAS B. BOWMAN.
